UNITED STATES PATENT OFFICE.

MORRIS SHERAS, OF CHICAGO, ILLINOIS, ASSIGNOR TO A. D. JOSLIN MANUFACTURING COMPANY, OF CHICAGO, ILLINOIS, A CORPORATION OF ILLINOIS.

DESIGN FOR A HAND STAMP.

Application filed August 28, 1922. Serial No. 3,590. Term of patent 14 years.

To all whom it may concern:

Be it known that I, MORRIS SHERAS, a citizen of the United States, residing at Chicago, in the county of Cook and State of Illinois, have invented a new, original, and ornamental Design for Hand Stamps, of which the following is a specification, reference being had to the accompanying drawing, forming a part thereof.

Fig. 1 is a side elevation of a stamp embodying the design;

Fig. 2 is a front elevation of the same; and

Fig. 3 is a rear elevation of the same.

I claim:

The ornamental design for a hand stamp substantially as shown.

MORRIS SHERAS.
